UNITED STATES PATENT OFFICE

107,647

DESIGN FOR A COMBINED TWIN BED RADIO AND LAMP

Joseph J. Herrera, Jr., Los Angeles, Calif.

Application February 9, 1937, Serial No. 67,540

Term of patent 3½ years

To all whom it may concern:

Be it known that I, Joseph J. Herrera, Jr., a citizen of the United States of America, residing at Los Angeles, in the county of Los Angeles and State of California, have invented a new, original, and ornamental Design for a Combined Twin Bed Radio and Lamp, of which the following is a specification, reference being had to the accompanying drawing, forming a part thereof.

Fig. 1 is a perspective view of the combined twin bed radio and lamp, showing my new design, and

Fig. 2 is an end view thereof;

The opposite side of the combined twin bed radio and lamp is the same or substantially similar to the side shown, while the rear face of the body is substantially plain.

I claim:—

The ornamental design for a combined twin bed radio and lamp, substantially as shown and described.

JOSEPH J. HERRERA, JR.
